US0D1077719S

(12) **United States Design Patent** (10) **Patent No.:** **US D1,077,719 S**
(45) **Date of Patent:** **** Jun. 3, 2025**

(54) **PERSONAL TRANSPORT VEHICLE**

(71) Applicant: **NantMobility, LLC**, Culver City, CA (US)

(72) Inventors: **Thomas M. Wittenschlaeger**, Sarasota, FL (US); **Rob Brady**, Sarasota, FL (US); **Erik Holmen**, Lakewood Ranch, FL (US); **Joel Chartier**, Lakewood Ranch, FL (US)

(73) Assignee: **NantMobility, LLC**, Culver City, CA (US)

(**) Term: **15 Years**

(21) Appl. No.: **29/981,258**

(22) Filed: **Dec. 30, 2024**

(57) **CLAIM**

The ornamental design for a personal transport vehicle, as shown and described.

DESCRIPTION

FIG. 1 is an isometric view of a personal transport vehicle in accordance with our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown are included for the purpose of illustrating portions of the article which form no part of the claimed design.

1 Claim, 7 Drawing Sheets
